CLAIM

The ornamental design for a frying pan, as shown and described.

DESCRIPTION

FIG. 1 is a top-front-left perspective view of a frying pan showing my new design;
FIG. 2 is a bottom-rear-right perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof; and,
FIG. 8 is a bottom plan view thereof.

The broken line showing a pan insert in FIGS. 1, 2, 7, and 8; and the handle in FIGS. 1, 2, 4, 5, 6, 7, and 8 are included for the purpose of showing environmental structure and form no part of the claimed design.
